US0D1112245S

(12) **United States Design Patent** (10) Patent No.: **US D1,112,245 S**
(45) Date of Patent: ** Feb. 10, 2026

(54) **DISPLAY SCREEN WITH GRAPHICAL USER INTERFACE**

(71) Applicant: **SONARDYNE INTERNATIONAL LIMITED**, Yateley (GB)

(72) Inventor: **Robert James Crook**, Castele Cary (GB)

(73) Assignee: **WAVEFRONT SYSTEMS LIMITED**, Dorset (GB)

(**) Term: **15 Years**

(21) Appl. No.: **29/813,024**

(22) Filed: **Oct. 26, 2021**

(51) LOC (15) Cl. **14-04**

(52) U.S. Cl.

USPC **D14/485**

(58) Field of Classification Search

USPC D14/485-495

See application file for complete search history.
